UNITED STATES PATENT OFFICE.

HERBERT STERLING WILSON, OF KIRKWOOD, MISSOURI, ASSIGNOR TO INLAND TYPE FOUNDRY, OF ST. LOUIS, MISSOURI, A CORPORATION.

TYPE-PERFECTING MECHANISM.

No. 908,634.

Specification of Letters Patent.

Patented Jan. 5, 1909.

Application filed April 22, 1903. Serial No. 153,781.

To all whom it may concern:

Be it known that I, HERBERT STERLING WILSON, a citizen of the United States, and a resident of the city of Kirkwood, county 5 of St. Louis, and State of Missouri, have invented certain new and useful Improvements in Type-Perfecting Mechanism, of which the following is a specification.

My invention relates to type perfecting 10 and consists in the parts and in the arrangements and combinations of parts hereinafter described and claimed.

In the accompanying drawings, which 15 form part of this specification, and wherein like symbols refer to like parts wherever they occur, Figure 1 is a side view of my perfecting mechanism; Fig. 2 is a diagrammatic view showing the connection of the perfecting mechanism to the actuating 20 mechanism; Fig. 3 is an end elevation of the perfecting mechanism; Fig. 4 is a plan view, partly sectional, of the actuating devices; and, Fig. 5 is a sectional detail of the 25 resilient plate for sustaining type in the channel. Fig. 6 is a perspective view of the inner side of the side plate with parts mounted thereon. Fig. 7 is a perspective view of the type carrier. Fig. 8 is a cross 30 section of the type carrier. Fig. 9 is a detail showing a modified form of the type gripping jaw of the type carrier, in which the upper inner surface of the gripping jaw is offset and provided with a resilient plate 35 or spring flush with its inner surface.

The perfecting mechanism is preferably 40 supported by a bracket 1 fixed to the main frame 2 of the type casting machine, which is preferably constructed as shown in my Patent No. 828,080, granted August 7, 1906.

The support for the type perfecting mechanism has guides thereon in which a type carrier 3 reciprocates preferably in direct alignment with the line of motion of the mold cover 4. At one end of this type carrier is 45 a type clamping device which consists of a bar 5 fitted with guides provided therefor in the supporting bracket so as to itself be free to slide relatively to the carrier. The endmost portion of the sliding bar or jaw slide 5 projects beyond the body of the carrier and is arranged so as to lie flush with 50 the top of the carrier and has a lateral offset 6 opposite the end of said body. In order to give some resiliency to the action of the 55 jaw slide, it is provided with a thin resilient

plate 6^a (as shown in Fig. 9.) The top of this offset portion is flush with the top of the carrier. In the space intervening between the end of the body of the carrier and the overhanging end of the jaw slide 5, 60 slides a vertically reciprocating ejector bar 7 mounted on the carrier so as to move therewith. In order to provide friction sufficient to hold the ejector bar in its adjusted position, it is provided with a spring 8^a which bears against the wall of its guide. A second spring 8 is mounted in the carrier in position to bear downwardly on said ejector bar and normally hold its top below the top of the carrier. The space between the end 70 of the carrier body and the overhanging end of the jaw slide constitutes the chamber which receives the type ejected from the clamping jaw 9 at the end of the mold cover of the type casting machine when the jaw 75 and chamber come into vertical alinement, and the vertically reciprocating ejector bar 7 constitutes the bottom of this chamber.

The type casting mechanism may be of any usual construction, wherein there is a 80 reciprocating mold cover, indicated at 4, equipped with a clamping device here typified by the clamping jaw 9 and the ejector 99, for ejecting the type from said jaw into the gripping jaw on the perfecting mechanism, when the mold cover has reached the 85 right-hand limit of its throw and the carrier its left-hand limit. This mechanism, which handles the unfinished type prior to its transfer into the type perfecting mechanism proper, is hereinafter designated as type 90 feeding mechanism, since it delivers the unfinished type directly to the perfecting mechanism and in the manner described further on.

Above the type carrier 3 and flush therewith is a cover 10 therefor. Fixed on one side of the cover is a perfecting knife 11 consisting of a plate having a series of sharp teeth adjusted to lie flush with or 100 slightly below the top edge of the type carrier and thereby be in position to trim the set shoulder of the type as the type is forced past it in the carrier. A second knife 12 is mounted with its teeth immediately under 105 the teeth of the first mentioned knife for the purpose of perfecting the under set shoulder of the type. By this arrangement, each type is rubbed and kerned separately. This last mentioned knife is mounted upon 110

a bar 13 which reciprocates in guides provided therefor in the side plate 43 of the frame of the perfecting mechanism transverse to the line of motion of the carrier. 5 This bar is normally held in its uppermost position by means of a spring 14 provided therefor, and carries at its lower portion a laterally projecting plate 15 whose front and rear edges are beveled so as to constitute inclined planes. This plate is arranged 10 with its upper surface parallel to the line of motion of the carrier and at such an elevation that a roller 16 provided for the purpose on the lower end of the ejector bar 7 will run flush with the upper surface of said plate, when said ejector bar is in its uppermost position, consequently, when said ejector bar is depressed, said roller will strike against the inclined plane or bevel at the 15 end of said plate 15 and thereby force the beveled plate downwardly. The downward movement of the beveled plate 15 carries with it the knife bar 13 and the lower knife 12. The purpose of this movement is to 20 automatically adjust the position of the lower knife 12 to the set of the type: for, as the ejector bar 7 of the type carrier 3 is normally held by its spring in its uppermost position, each type forced against it 25 when injected into the clamp by the ejector 30 99 of the type casting machine will depress said ejector bar 7 a distance exactly equal to the set of that particular type; and as the beveled plate 15 is likewise depressed an 35 amount equal to the depression of the roller on said ejector bar, the knife 12 which is movable with said plate 15 is itself depressed to an amount equal to the set of that particular type. 40 The cover 10 of the type dresser has a channel 17 extending upwardly from the lower face thereof, said channel being of sufficient width to admit type of different body thicknesses. One side of this channel 45 has a metal spring 18 set therein, which spring consists of a flat plate mounted upon a suitable support and tapering downwardly to its end. The position of this spring can be adjusted by means of a screw 50 bearing against it. Close to its lower end the inner side of this spring is beaded or otherwise provided with a slight protuberance 19 arranged to constitute a stricture for the bottom of the channel, whereby said 55 spring tends to clamp and prevent the dropping of the type forced into the mouth of said channel from below. Along the sides of the vertical portion of this channel are arranged two knives 20 opposite each other 60 and adjustably mounted to trim the body shoulders of the type. 65

Mounted to slide vertically in guides on the frame of the perfecting mechanism in alignment with the vertical channel is a bolt or bar 21 whose upper end normally

rests in such a position that the lower end of the ejector bar 7 in its lowermost position will just clear the upper end of said sliding bolt. The lower end of this sliding bolt is in position for the outer end of a lever 22 70 to bear against it. The fulcrum of this lever is supported preferably on the framework of the type casting machine and its inner end is provided with an antifriction wheel 23 arranged to bear against the 75 periphery of an edge cam 24 provided therefor on the cam shaft 25 of the machine. The free end of this lever is provided with a vertically adjustable screw 26 which is the immediate device for transmitting motion 80 from said lever to the vertically sliding bolt 21. In consequence of this arrangement, the movement of the cam shaft 25 causes the rocking of the lever 22 whose motion in turn is transmitted into the vertical movement of the sliding bolt 21. The vertical movement of the sliding bolt 21 is transmitted through the adjustable screw 26 to the ejector bar 7, the various movements being 85 so timed that the ejector bar is immediately 90 above the sliding bolt while said sliding bolt is moving. Consequently, during the upward movement of the sliding bolt, the type, which at that time registers with the vertical channel 17, is forced upwardly into 95 said channel. The protuberance 19 on the spring at the end of the channel prevents the dropping of the type when the ejector bar is returned to its normal position.

By the arrangement of the channel 17 vertically above the type carrier, the weight of the superimposed type in the channel steadies the successive type in their passage past the knives 20 and the vertically reciprocating bar 7, which serves as the bottom of 100 the type chamber in the carrier and as a part of the automatic means for adjusting the knife 12, also serves as the ejector for removing the type from the carrier and forcing them past the knives 20. 105

The reciprocation of the type carrier is effected from the cam shaft 25. For this purpose the cam shaft has a cam 27 thereon against which bears the end of a drag bar 28 mounted to slide longitudinally in supports provided therefor in the frame of the type casting machine. An antifriction wheel 23 on the end of said drag bar is held against said cam by means of a spring 29 provided for the purpose. On its outer end, 110 the drag bar 28 has a laterally extending pin 115 30. On the frame of the perfecting mechanism is mounted a vertical lever 31 whose lower end is connected to the outer end of said drag bar and whose upper end is connected by a link 32 to the carrier. 120

By this arrangement of power transmitting devices the reciprocation of the type carrier is effected from the cam shaft. It is desirable, however, to provide means where- 125

by the length of the stroke of the carrier may conform exactly to the distance between the clamping jaw of the casting machine and the type channel; and it is also 5 desirable to provide means whereby the limiting positions of said type carrier shall coincide with said clamping device of the casting machine and said type channel respectively. The length of the stroke of the 10 type carrier is regulated by shifting the point at which the drag bar 28 is connected to the vertical lever 31. For this purpose, the lower end of the lever is slotted lengthwise and the link 32 which connects said 15 drag bar to said lever, is provided with a transversely arranged clamping pin 33 adapted to slide in said slot and be clamped at any desired position therein. In order to regulate the limiting positions of said type 20 carrier, the link 32 which connects the drag bar to the vertical lever is made adjustable lengthwise, as by means of threaded sections connected together by a turnbuckle 34. The lengthening of this link has the effect 25 of moving the type carrier forward; and after the stroke of the type carrier has been properly adjusted, said link is adjusted so as to get the limiting positions of said type carrier at the desired points.

30 The type carrier has a lever 35 pivotally mounted on its side. The upper end of this lever is slotted to receive a pin 36 which projects from the jaw slide 5. The lower end of this lever has an adjusting screw 37 35 extending therethrough in position to strike against a projection or abutment 38 provided therefor on the side of the frame of the perfecting mechanism immediately before the carrier reaches the forward limit 40 of its stroke. When the adjusting screw on said lever strikes said projection, it causes the lever to swing on its pivot and thereby move the jaw slide forwardly relative to said carrier. By this arrangement, the jaw 45 slide, which is normally held against the end of the carrier by means of its spring 42, is separated therefrom a sufficient distance to permit the type to enter the space between them.

50 In order to relieve the shock due to the momentum of the carrier, the supporting frame is provided with a rod 39 which projects rearwardly therefrom through a yoke 40 mounted on said carrier. This rod is 55 screw-threaded and provided with adjusting nuts 41 which are adjusted to the proper positions to be struck by the carrier at the very limit of its movement.

Obviously, the construction hereinbefore 60 described may be changed considerably without departing from my invention, and I do not wish to restrict myself to such constructions.

What I claim is:

65 1. In a machine for perfecting type, a

frame, a type carrier arranged to reciprocate therein, rubbing or kerning knives arranged to dress the type in the carrier, said knives being so mounted as to be automatically relatively adjustable transversely to the 70 line of travel of the carrier and with respect to one another, and type-controlled means to effect said adjustment.

2. In a machine for perfecting type, a 75 frame, a type carrier arranged to reciprocate therein, rubbing or kerning knives arranged to dress the type in the carrier, said knives being so mounted as to be automatically relatively adjustable transversely to the 80 line of travel of the carrier and with respect to one another, and automatically acting means to effect said adjustment, said means being constructed to control and vary the extent of said adjustment in accordance 85 with the set of the individual type in the carrier.

3. In a machine for perfecting type, a 90 frame, a type carrier arranged to reciprocate therein, rubbing or kerning knives arranged to dress the type in the carrier, said knives being so mounted as to be automatically relatively adjustable transversely to the 95 line of travel of the carrier and with respect to one another, a part set to a definite position by the insertion of the type in the carrier, and a part connected to the knives and located in the path of the part set by the type to be moved thereby as the carrier advances the type to said knives.

4. In a machine for perfecting type, a 100 frame, a movable type carrier therein, and perfecting knives arranged to dress the type in the carrier, one of said knives being stationary and the other knife being mounted upon a bar arranged to slide transversely 105 to the line of motion of the carrier, and means for actuating said bar, said means being arranged to be adjusted automatically by forcing the type into said carrier.

5. In a machine for perfecting type, a 110 frame, a type carrier arranged to reciprocate therein, and perfecting knives arranged to dress the type in the carrier, one of said knives being stationary and the other knife being mounted upon a bar arranged to slide transversely to the line of motion of the carrier, and means for actuating said bar, said means being arranged to be adjusted automatically 115 by forcing the type into said carrier.

6. In a machine for perfecting type, a 120 frame, a movable type carrier therein and perfecting knives arranged to dress the type in the carrier, a bar arranged to slide transversely to the line of motion of the carrier, 125 one of said knives being stationary, the other knife being mounted upon said bar, and said carrier having a spring actuated plunger arranged to be pressed back by the type and being also arranged to actuate said 130

sliding bar more or less according to its varying positions as determined by said type.

7. In a machine for perfecting type, a frame, a type carrier arranged to reciprocate therein, and perfecting knives arranged to dress the type in the carrier, a bar arranged to slide transversely to the line of motion of the carrier, one of said knives being stationary, the other knife being mounted upon said bar, and said carrier having a spring actuated plunger arranged to be pressed back by the type and being also arranged to actuate said sliding bar more or less according to its varying positions as determined by said type.

8. In a machine for perfecting type, a frame, a type carrier arranged to reciprocate therein, and perfecting knives arranged to dress the type in the carrier, a bar arranged to slide transversely to the line of motion of the carrier, one of said knives being stationary, the other knife being mounted upon said bar, and said carrier having a friction retained plunger arranged to be pressed back by the type and being also arranged to actuate said sliding bar more or less according to its varying positions as determined by said type, said bar having a horizontally extending projection arranged in the path of the lower end of said plunger and the upper surface of said projecting portion being inclined downwardly towards its inner end to a point flush with or below the co-operating portion of said plunger whereby the knife is depressed a distance equal to the depression of said plunger.

9. A type perfecting mechanism comprising a frame, a type carrier arranged to reciprocate horizontally therein, a gripping jaw arranged to slide lengthwise of said carrier, and means for normally keeping said gripping jaw closed, said gripping jaw having its end portion projecting parallel with the end of said carrier and an automatically acting lever fulcrumed on said carrier, one end of said lever being pivotally connected to said sliding jaw and the other end being arranged to strike a stationary projection when the carrier approaches the inner limit of its stroke.

10. A type perfecting mechanism comprising a frame, a type carrier arranged to reciprocate horizontally therein, a gripping jaw arranged to slide lengthwise of said carrier, and means for normally keeping said gripping jaw closed, said gripping jaw having its end portion projecting parallel with the end of said carrier and a lever fulcrumed on said carrier, one end of said lever being pivotally connected to said sliding jaw and the other end being arranged to strike a stationary projection when the carrier approaches the rearward limit of its stroke.

65 11. In a machine for perfecting type, a

frame, a type carrier arranged to reciprocate therein, and perfecting knives arranged to dress the type in the carrier, a bar arranged to slide transversely to the line of motion of the carrier, one of said knives being stationary, the other knife being mounted upon said bar, and said carrier having a spring-actuated plunger arranged to be pressed back by the type and being also arranged to actuate said sliding bar more or less according to its varying positions as determined by said type, and means arranged to move said plunger to eject said type when the carrier reaches the rearward limit of its movement.

70 12. In a type making machine, a type perfecting mechanism comprising in combination a horizontally reciprocating type carrier having a type clamping device adapted to grip an undressed type, dressing knives arranged along the path of said carrier in position to dress the type carried thereby, a channel extending vertically above the carrier, a vertically movable bar for ejecting said type upwardly into said channel, means for actuating said bar, and dressing knives 75 arranged along the sides of said channel.

80 13. In a type making machine, a type perfecting mechanism comprising in combination a horizontally reciprocating type carrier having a type clamping device adapted to grip an undressed type, dressing knives arranged along the path of said carrier in position to dress the type gripped therein, a channel extending vertically above the carrier, a vertically movable bar adapted to 85 eject said type upwardly into said channel, and dressing knives arranged along the sides of said channel, the lower end of said channel having a type supporting device to hold the type in place on the retraction of 90 the ejector bar.

95 14. In a type making machine, a type perfecting mechanism comprising in combination a horizontally reciprocating type carrier having a type clamping device adapted to grip an undressed type, knives arranged along the path of said carrier in position to dress the type gripped therein, a channel extending vertically above the carrier, means for ejecting said type upwardly into said 100 channel when the clamping device comes into alignment with the channel, dressing knives arranged along the sides of said channel, and a resilient gate at the lower end of said channel arranged to support the type 105 therein.

110 15. In a type perfecting mechanism, the combination of a type carrier, a type clamping device on said carrier into which said type are fed, a vertically reciprocating bar entering said clamping device from beneath and depressed by the type fed in, type dressing knives arranged along the path of the carrier, a channel extending vertically above the carrier, and means for moving said bar 115

upwardly through the clamp to eject the type from the clamp into said channel.

16. In a type perfecting mechanism, the combination of a type carrier, a type clamping device on said carrier into which said type are fed, a vertically reciprocating bar entering said clamping device from beneath and depressed by the type fed in, type dressing knives arranged along the path of the carrier, means operated by said bar for relatively adjusting said knives to the set of the type in the clamping device, a channel extending vertically above the carrier, and means for moving said bar upwardly through the clamp to eject the type from the clamp into said channel.

17. In a type perfecting mechanism, the combination of a frame, a type carrier arranged to reciprocate therein and having a type clamping device thereon, for receiving type at one limit of travel of the carrier and means at the other limit of travel of the carrier for discharging the type from the clamping device, type perfecting devices operating on the type as it is carried along, and means for adjusting the length of the stroke of the type carrier to the distance between the type receiving position and the position for discharging the type.

18. In a type perfecting mechanism, the combination of a frame, a type carrier arranged to reciprocate therein and having a type clamping device thereon, for receiving type at one limit of travel of the carrier and means at the other limit of travel of the carrier for discharging the type from the clamping device, type perfecting devices operating on the type as it is carried along, means for adjusting the length of the stroke of the type carrier to the distance between the type receiving position and the position for discharging the type, and means for adjusting the limits of the stroke of said carrier to make them coincide with the feeding and said discharging position.

19. In a type perfecting mechanism, the combination of a frame, a type carrier arranged to reciprocate therein and having a type clamping device thereon, for receiving type at one limit of travel of the carrier and means at the other limit of travel of the carrier for discharging type from the clamping device, type perfecting devices operating on the type as it is carried along, a lever connected to said type carrier to actuate the same, driving mechanism, and connecting devices connecting said lever and said driving mechanism, the point of attachment of the connecting devices to said lever being

adjustable lengthwise of the lever to vary 60 the length of stroke of the carrier.

20. In a type perfecting mechanism, the combination of a frame, a type carrier arranged to reciprocate therein and having a type clamping device thereon, for receiving 65 type at one limit of travel of the carrier and means at the other limit of travel of the carrier for discharging type from the clamping device, type perfecting devices operating on the type as it is carried along, 70 a lever connected to said type carrier to actuate the same, driving mechanism, and connecting devices connecting said lever and said driving mechanism, the point of attachment of the connecting devices to said lever 75 being adjustable lengthwise of the lever, and said connecting devices being extensible to make the limits of the stroke of said carrier coincide with the feeding and discharging position.

21. In a type perfecting mechanism, the combination of an automatically opening and closing type gripping jaw adapted to reciprocate from and towards a point where type may be fed thereto and arranged and constructed to receive type when at this point, and perfecting knives arranged along the path of said gripping jaw to dress the type as they are carried past them.

22. A type making machine, comprising 90 a type gripping device consisting of a main piece and a slide movable longitudinally thereof, said slide having a clamping jaw extending laterally therefrom opposite the end of said main piece, the inner face of said 95 clamping jaw being offset and provided with a resilient plate arranged over the offset portion, and a plunger arranged to reciprocate between the main piece and the clamping jaw.

23. A type perfecting mechanism, comprising a reciprocating type carrier consisting of a main piece and a slide movable longitudinally thereof, said slide having a clamping jaw laterally projecting therefrom 105 opposite the end of said main piece, the inner face of said clamping jaw being offset and provided with a resilient plate arranged over the offset portion, and a plunger arranged to reciprocate between the main 110 piece and the clamping jaw.

Signed at St. Louis, Missouri, this 18th day of April, 1903.

HERBERT STEERLING WILSON.
